UNITED STATES PATENT OFFICE.

RUDOLF SCHMIDT, OF CINCINNATI, OHIO.

BOSOM-STRETCHER.

SPECIFICATION forming part of Letters Patent No. 256,384, dated April 11, 1882.

Application filed December 1, 1881. (Model.)

To all whom it may concern:

Be it known that I, RUDOLF SCHMIDT, of Cincinnati, Ohio, have invented a new and useful Improvement in Bosom-Stretchers, of which the following is a specification.

My invention relates to improvements in those ironing-boards which are adapted to support in a condition suitable for ironing a shirt or similar article of apparel.

10 My device consists essentially of a base or foot, a post or upright secured thereto, a board hinged to the top of the post or upright to adapt the board to be rocked or seesawed, a clamp for tightly gripping the skirt of the garment, and means for depressing the remote end or head of the board while the foot of the board is elevated, so as to stretch the garment tightly upon the board, as hereinafter described and claimed.

20 In the accompanying drawings, Figure 1 is a perspective view of my device in condition for use. Fig. 2 is an end elevation of the same. Fig. 3 is a section on the line $x-x$, Fig. 2. Figs. 4, 5, 6, and 7 represent modifications 25 of my device. Fig. 8 is an under side view of the modification, Fig. 7.

A is a board or slab constituting the base of the machine.

B is an upright, to whose top edge is hinged 30 or fulcrumed at C another board, D, which constitutes the rest or support upon which the shirt or other garment is laid to be operated upon. In order that the rocking of the rest D shall at the same time impart to it a longitudinal 35 motion, the said hinge is located at the lower extremity of an arm, E, which projects rigidly downward from the said rest. The said arm is located upon the board, somewhat to the right of its center of gravity, so as to cause the left end to slightly preponderate.

40 Hinged at F to the right-hand end of the base, and capable of occupying a notch, d, in the right-hand end of said rest D, is a post, G, to which is pivoted a cam-headed lever, H, the periphery of whose head rests, when in use, upon the right-hand end of the said board D.

45 A pair of open-notched projections, J J', afford journal-bearings for a removable jaw or clamp, K.

My device is operated as follows: The shirt 50 having been drawn over the board D and its skirt made to occupy the base between the projections J J', the clamp K is applied, as indicated in Fig. 1. The right-hand end of the board D is then depressed by hand, and the 55 cam-post G is made to occupy the notch d, the cam-lever H being in its relaxed condition. These motions operate to slightly stretch the shirt upon the rest D, and the cam-lever H being now depressed, a still further lowering of 60 the right end and simultaneous elevation of the left end result, by which the shirt becomes stretched taut over the said rest in suitable condition for ironing. A reversal of the above actions liberates the shirt and permits its re- 65

The above-described preferred form of my invention may be modified in non-essential particulars. For example, the hinged post may be screw-threaded, as at G', Fig. 4, for a nut, H', 70 which discharges the functions of the cam-lever H; or a spring-pawl, L, may engage in a fixed ratchet, M, as in Fig. 5; or the rest-arm may be prolonged downward, as in Fig. 6, and have coupled to it a nut, N, that receives 75 a screw-threaded winch, P; or such prolonged arm may, as in Figs. 7 and 8, occupy an oblique slot, q, in a lever, Q.

I claim as new and of my invention—

1. A bosom-stretcher board, D, hinged to a 80 standard and adapted to be rocked thereon, in combination with a clamp for gripping the skirt of the garment and a device for depressing the head of the board and elevating the foot thereof, as set forth.

2. The combination, with a base, A, standard B, skirt-clamping device K, board or rest D, having arm E, hinged to the standard, and a tipping device adapted to depress the head and elevate the foot of the board or rest, as 90 set forth.

3. The combination, with base A, provided with standard B and skirt-gripping and board-tipping devices, of the tipping or rocking board or rest D, having the arm E, hinged to the 95 standard B, substantially as set forth.

4. In combination with the rocking board or rest D E, standard B, base A, and a rest-

depressing device, the removable jaw or clamp K and open-notched bearings J J', substantially as set forth.

5. In combination with the rocking board or rest D E, standard B, and base A and skirt-clamp, the rest-depressing cam-lever H, fulcrumed in hinged post G, that occupies a notch, d, in the said rest and is removable therefrom, substantially as set forth.

In testimony of which invention I hereunto set my hand.

RUDOLF SCHMIDT.
